(57) **CLAIM**

I claim the ornamental design for an anchoring device, as shown and described.

DESCRIPTION

FIG. 1 is a side and front side perspective view of the anchoring device showing my new design; FIG. 2 is a front, side and upper end perspective view thereof;

FIG. 3 is a side and front perspective view similar to FIG. 1 but angled slightly further toward the side;

FIG. 4 is another side and front perspective view thereof, angled more toward the side than in the preceding views;

FIG. 5 is a side and rear perspective view thereof;

FIG. 6 is another side and rear perspective view thereof, angled more toward the side than in FIG. 5;

FIG. 7 is another front and side perspective view, angled more toward the side than in the preceding figures;

FIG. 8 is a front elevational view thereof;

FIG. 9 is a side elevational view thereof;

FIG. 10 is a rear elevational view thereof;

FIG. 11 is an elevational view of the lower end as oriented in FIG. 1;

FIG. 12 is an elevational view of the upper end as oriented in FIG. 1;

FIG. 13 is a side and front perspective view similar to FIG. 3 but showing the design in accordance with environmental structure;

FIG. 14 is a side and rear perspective view similar to FIG. 5 but showing the design in association with additional environmental structure; and,

FIG. 15 is a side and front perspective view similar to FIG. 7 and showing the design in association with environmental structure.

The broken lines are included for the purpose of illustrating the portions of the anchoring device and associated structures that form no part of the claimed design.

The anchoring system of the claimed design is a trademark of PROCONTROL SOCCER INC®.
